GARAGE DOOR OPERATOR

Odessa D. Boardman, Chester, Tex.

Application September 23, 1938, Serial No. 231,422

10 Claims. (Cl. 268—31)

My invention relates generally to vehicle operated doors and particularly an arrangement of this type in which the door per se collapses vertically to open and closed positions, and an important object of my invention is to provide a relatively simple, practical, and rugged device of this kind.

Another important object of my invention is to provide, in an arrangement of the character indicated above, means for positively producing smooth, unhurried, and shock protected door opening and closing means, positively providing for smooth action protecting the mechanism against undue wear and tear.

Other important objects and advantages of my invention will be apparent from a reading of the following description taken in connection with the drawings, wherein for purposes of illustration I have shown a preferred embodiment of my invention.

20 In the drawings:

Figure 1 is a general front elevational view showing a garage equipped with a door in accordance with the present invention.

25 Figure 2 is a top plan view of Figure 1 showing the entrance and exit pavement outside of the garage, and showing the roof of the garage partly broken away to show a portion of one of the vehicle operated elements, within the garage.

30 Figure 3 is a contracted transverse vertical sectional view taken through Figure 2 approximately on the line 3—3 and looking upwardly in the direction of the arrows.

Figure 4 is a longitudinal vertical sectional view taken through Figure 2 approximately on the line 4—4 and showing one set of the operating elements at rest and in inoperative positions and with the door closed.

35 Figure 5 is a fragmentary view similar to Figure 4 but showing the chock within the garage in the depressed operated position in full lines and in the elevated initial position in dotted lines.

Figure 6 is an elevational view of one of the door posts showing the guides for the door sections and the middle slot in the door post for receiving the guide on the end of the door assembly.

40 Figure 7 is a transverse vertical sectional view taken through Figure 1 approximately on the line 7—7 and looking toward the left in the direction of the arrows.

Figure 8 is a horizontal sectional view taken through Figure 7 approximately on the line 8—8 and looking downwardly in the direction of the 45 arrows.

Figure 9 is a horizontal sectional view taken through Figure 1 approximately on the line 9—9 and looking downwardly in the direction of the arrows.

Figure 10 is a transverse vertical sectional view taken through Figure 9 and showing the door sections in expanded positions.

Figure 11 is a transverse vertical sectional view taken through Figure 12 and showing the door sections in the fully collapsed closed position.

Figure 12 is a front elevational view of a left hand portion of the door assembly.

Figure 13 is a transverse vertical sectional view taken through one of the shock absorber cylinders, taken approximately on the line 13—13 of Figure 7.

Figure 14 is a front elevational view of a left hand portion of the door assembly showing the guide thereof extending through the slot in the adjacent door post.

Referring in detail to the drawings, the numeral 5 generally designates a garage or other building whose entrance is bounded at the sides by the respective door posts 6 and 7 in which the door assembly generally designated 8 works. In front of the entrance is the entrance and exit pavement which is generally designated 9 and within the garage is the floor 10. Suitably accommodated in twin depressions in the exit and entrance pavement 9 are the treads 11 and 12 which are hinged as indicated by the numerals 13 and 14 at their approach ends and have depending pivotally from the normally elevated inner ends thereof the links 15 which are connected to brackets thereon as indicated by the numeral 16 and have their lower ends pivotally connected to the rigid arm 17 which projects from the rock shaft 18 as indicated in Figures 4 and 8. This arrangement is such that when the vehicle runs along the treads 11 and 12 in approaching the garage door, the normally elevated ends of the treads will be depressed so as to swing the shaft 18 in a counterclockwise direction viewed in Figure 4.

Within the garage 5 are the treads 20 and 21 which are pivoted as indicated by the numerals 22 and 23 at their ends to brackets 24 which depend from the garage floor portion 25, the normally elevated ends of the treads 20 and 21 adjacent the entrance of the garage having depending therefrom the link 26 similar to the links 15 pivotally connected as indicated by the numeral 27 to a bracket on the bottom of the treadle, the lower end of this link being pivotally connected as indicated by the numeral 28 to the

arm 29 which projects rigidly from the rock shaft 18' which is companion to the rock shaft 18 already described. The treadles 20 and 21 have formed therein a slot 29 in which works a chock 30 which is pivoted as indicated by the numeral 31 at one end to one end of the slot 29, said chock normally being in an elevated position as illustrated in Figure 4 by reason of connection of the arm 32 thereof pivotally as indicated by the numeral 33, to the upper end of a link 34 which is pivotally anchored to an anchor 35 below the floor of the garage. A swingable ramp 36 pivoted as indicated by numeral 37 to the edge of the floor portion 25 adjacent to the chock, gravitationally 15 adjusts itself to the positions of the treadles 20, 21 and the floor portion 25 for smooth entrance and exit of the automobile or the like relative to the garage. The chocks 30 are provided to prevent precipitate movement of the automobile in 20 the garage toward the door in effecting an exit from the garage, by acting to impede the progress of the automobile toward the door and at the same time start the gradual depression of the treadles 20, 21 so as to effect smooth operation of 25 the treadles due to the passage of the automobile toward the garage door. Without such arrangement, there is constant danger that the automobile, in making its exit movement would not only unduly quickly start the depressing movement of 30 the treadles 20, 21, but would be apt to ram into the garage door before the door had been fully opened by responsive action of the door opening mechanism.

The mentioned shafts 18 and 18' are supported 35 in respective bearings 40, 41 at the opposite ends of the pit below the level of the garage floor, and at the opposite end of these shafts are pairs of inwardly tending rigidly connected arms 44, 45 and 46, 47 which extend through accommodating 40 openings in the vertically elongated generally rectangular enclosures 48 which are disposed outside of the door posts 6 and 7, respectively, and slightly spaced therefrom as clearly shown in Figure 3 of the drawings. Pivotally connected to the free ends of the mentioned arms are the 45 pairs of companion legs 49, 50 and 51, 52, the respective pairs having their upper ends converging and connected to the same pivots 53, 54 secured to the respective inner and outer sides 50 of the weight member which is generally designated 55 and which are, in their initial positions of rest, sufficiently heavy to positively prevent operation of the garage door from the outside from a closed to an open position by any normal 55 agency other than vehicle operation of the outside treadles 11, 12. However, when, for instance, the treadle 11 is depressed by the passage of an automobile thereon, and the normally elevated end thereof is depressed, the rock shaft 18 is swung in a counterclockwise direction, as 60 seen in Figure 4, and because of the mechanical connection of the shaft 18 with the shaft 18', the shaft 18' is rotated in the opposite direction in the same amount, so that the fixed arms 44, 45, and 46, 47 swing in an upward direction and in so doing carry the weight members 55 upwardly away from their initial positions of rest.

When this elevation of the weight members takes place, the counterbalance weights 56, 57 65 having cables 58, 59 trained over drums 60, 61 secured to shafts 62 journaled in the laterally inward wall 63 of the enclosure 48 and the laterally outward wall 64 of the enclosures including a pulley 65 over which is trained an endless 70 belt 66 which is also trained over a pulley 67, and

a shaft 68 similarly journaled between the opposing walls of the enclosure 48; the shaft 68 having thereon a drum 68 over which is trained a cable 69 which is turned around the drum 68 and fastened at its free end as indicated by the 5 numeral 70 to the back wall of the enclosure 48 after passing over a pulley 71 fastened to the top of the weight member by a bracket 72; so that as the weight members are lifted the counterbalance weights 56 and 57 are freed to pull down 10 on their cables 58 and 59 and thereby rotate the shafts 62 and 68, which action, through the connection of the cable 69 with the weight members helps to elevate the weight members smoothly, especially in starting and in reaching their upper 15 limits, at which position of the weight members the door is in a fully opened position.

For absorbing the shock incident to the weight members reaching their upward limits, there are provided air or liquid containing shock absorber 20 cylinders 75 and 76 which are similar in construction and are individually supported by brackets 77 and 78 extending between the wall members 63 and 64 of the enclosure 48, the cylinders depending from these brackets being 25 substantially open at their lower ends and provided with a retainer 79 which retains a floating piston which is generally designated 80 and which comprises a valve cage 81 with a reduced opening 82 leading into the ball valve seat 83 in which is 30 a free ball 84. The top of the shock absorber cylinder is provided with a fitting 85 in the form of a valve to control the escape of compressed fluid above the piston as the piston is forced upwardly by reason of engagement thereof by the 35 standard 86 which projects from the top of each of the weight members 55, for the purpose.

To absorb the shock of the weight members reaching the low point, in the act of returning to their initial positions, standards 87 and 88, 40 suitably anchored on the bottom of the pit 43 each connect with a hydraulic piston 89, 90 which operates in a conformably shaped opening in the bottom of the weight member as indicated by the numeral 91 in Figure 3. Regulating the escape of fluid from the opening 91 above the pistons 89 and 90 is the valve equipped passage 92 which opens through the side of the weight member, the valve therein being adjustable to produce the desired seating of the weight members in returning to their initial positions.

In the spaces between the door posts 6 and 7 and the adjoining walls 63 of the enclosures 48 and at the lower ends of the door posts are the pulleys 93 and 94 over which are trained the 55 endless cables 95 and 96, respectively, which are also trained over the pulleys 97 and 98 which are fixed to the laterally inward ends of the shafts 62 at the upper ends of the door posts. Portions of the door 8 at the opposite edges thereof are 60 operatively connected with the cables 95 and 96 so that when the shafts 62 are rotated in the required direction, the door will be either opened from a closed position, or closed from an open position.

Each of the door posts 6 and 7 is provided centrally with the vertically elongated slot 100, at both sides of which are vertical channel guides 101 and 102, respectively, which are of different vertical lengths corresponding to the vertical 70 lengths of the sections which compose the collapsible door, and the opposite ends of the door sections are slidably disposed in these guides which have closed bottoms located at the point of elevation above the garage floor at which the 75

particular door sections come to rest in extending the door to fully closed position, the guides thereby acting not only as runners for the door sections but also as stops.

5 The door is composed of a central section 103 which has screwed as indicated by numeral 104 to the bottom edge thereof the retainer 105 which is the full length and width of the door so that when the section 103 is elevated the member 105 will engage the bottoms of the other sections 106 and 107, positioned respectively in the guides 101 and 102, so as to elevate the sections in the opening action of the door until the edges of the member 105, extending beyond the front and back sections, engage the lower edges of the stops 108 and 109 which are suspended in the upper part of the entrance of the garage.

As indicated in Figures 9 and 10 the door sections 108 and 109 and the centralized section 20 103 do not have their end edges inserted in the channel guides 101 and 102 respectively, but opposed plates 110 and 111 receive double edged portions of the ends of the sections and then come together as indicated by the numeral 112 to form an element smaller in thickness than the section and to enter the guides as clearly shown in Figure 9. The portions 112 of adjacent sections have straps 113 connected therebetween on one side of the door and 114 at the opposite side of the door as clearly indicated in Figure 10, the straps being securely anchored as indicated by the numerals 115 and 116, respectively, at their lower ends and similarly at their upper ends as indicated by the numerals 117 and 118, the connection being made to the laterally outward sections and the laterally inward sections with respect to any pair of sections by means of slide brackets 119 and 120, respectively, which slide along the straps 113 and 114, thereby securely but slidably assembling the sections to form the door assembly.

The plates 110 and 111 of the central section 103 extend further beyond the edges of the section 103 and merge into a headed shank 121 which passes through the slot 100 and through a clamp 122 which clamps to one flight of a corresponding one of the endless cables 95 and 96, by reason of which connection the operation of the cables raises and lowers the door 8 and in 50 so doing contracts or expands various sections 108 and 109 and 103. As indicated in Figure 3 of the drawings a floor element 123 is provided between the adjacent ends of the outside and inside treadles to bridge the distance therebetween and provide smooth passage of the automobile between the inside and outside treadles.

As an automobile approaching the garage and operating the outside treadles 11 and 12, respectively, accomplishes substantially full depression 60 of the said treadles, the action of the linkage connected to the shafts 18 and 18' will have elevated or collapsed the door 8. As soon as the automobile passes into the garage and the rear wheels thereof leave the inside treadles 20 and 21 and come upon the floor 10 and the portion 25 thereof, the front wheels of the vehicle passing over the chocks 30 while the treadles 20 and 21 are still partially depressed and the chocks depressed, the treadles 20 and 21 will rise behind 70 the vehicle as will the chocks 30, and by this action condition the operation of the weight elements and the counterbalances to return the car door to open extended position. To take the car out of the garage, the same is run in the opposite direction so as to engage and gradually de-

press the chocks 30 and consequently the treadles 20, 21, thereby effecting collapsing or opening movement of the door, and the vehicle is then guided out of the garage and onto the treadles 11 and 12. As the vehicle leaves the pivoted and normally depressed end of the treadles 11 and 12 and permits the opposite ends thereof to rise, this action of the treadles conditions the weight elements and the counterbalances to restore the door 8 to the expanded or closed position.

Although I have shown and described herein a preferred embodiment of my invention, it is to be definitely understood that I do not desire to limit the application of the invention thereto, and any change or changes may be made in the materials and in the structure and arrangement of the parts, within the spirit of the invention and the scope of the subjoined claims.

Having described the invention, what is 20 claimed as new is:

1. A device of the character described comprising a door having vertically movable elements movable upwardly to open position and downwardly to closed position, guide and stop means at the side of the door for guiding the vertical movement of said elements and limiting their downward travel, first treadles and second treadles, weight means holding the door in closed position, operating connections between the first 25 and second treadles for elevating said weight means, counterweight means operatively connected to the door and to said operating connections, said counterweight means being operative by gravity upon elevation of said weight means 30 to operate said movable elements of the door to elevated open position.

2. A device of the character described comprising a door having vertically movable elements movable upwardly to open position and downwardly to closed position, guide and stop means at the side of the door for guiding the vertical movement of said elements and limiting their downward travel, first treadles and second treadles, weight means holding the door in closed 40 position, operating connections between the first and second treadles for elevating said weight means, counterweight means operatively connected to the door and to said operating connections, said counterweight means being operative 45 by gravity upon elevation of said weight means to operate said movable elements of the door to elevated open position, said first and second treadles being longitudinally aligned and located on opposite sides of the door.

3. A device of the character described comprising a door having vertically movable elements movable upwardly to open position and downwardly to closed position, guide and stop means at the side of the door for guiding the vertical 50 movement of said elements and limiting their downward travel, first treadles and second treadles, weight means holding the door in closed position, operating connections between the first and second treadles for elevating said weight 55 means, counterweight means operatively connected to the door and to said operating connections, said counterweight means being operative by gravity upon elevation of said weight means to operate said movable elements of the door to 60 elevated open position, said first and second treadles being longitudinally aligned and located on opposite sides of the door, said second treadle being positioned at the rear side of the door, a chock pivoted on said second treadle for engage- 65

- ment by the leading wheel of a vehicle retreating toward the door, said chock having support independent of said second treadle and being operatively connected to said second treadle 5 whereby precipitate retreat of the vehicle and sudden operation of the second treadle is prevented and gradual operation thereof provided for.
4. A device of the character described comprising a door having vertically movable elements movable upwardly to open position and downwardly to closed position, guide and stop means at the side of the door for guiding the vertical movement of said elements and limiting their downward travel, first treadles and second treadles, weight means holding the door in closed position, operating connections between the first and second treadles for elevating said weight means, counterweight means operatively connected to the door and to said operating connections, said counterweight means being operative by gravity upon elevation of said weight means to operate said movable elements of the door to elevated open position, first fluid shock absorber means mounted below and engageable by said weight means for easing the subsiding of said weight means from an elevated to the depressed initial position of said weight means.
5. A device of the character described comprising a door having vertically movable elements movable upwardly to open position and downwardly to closed position, guide and stop means at the side of the door for guiding the vertical movement of said elements and limiting their downward travel, first treadles and second treadles, weight means holding the door in closed position, operating connections between the first and second treadles for elevating said weight means, counterweight means operatively connected to the door and to said operating connections, said counterweight means being operative by gravity upon elevation of said weight means to operate said movable elements of the door to elevated open position, said operating connections comprising crossed and pivoted lever means.
6. A device of the character described comprising a door having vertically movable elements movable upwardly to open position and downwardly to closed position, guide and stop means at the side of the door for guiding the vertical movement of said elements and limiting their downward travel, first treadles and second treadles, weight means holding the door in closed position, operating connections between the first and second treadles for elevating said weight means, counterweight means operatively connected to the door and to said operating connections, said counterweight means being operative by gravity upon elevation of said weight means to operate said movable elements of the door to elevated open position, said operating connections comprising two parallel rock shafts, first and second arms projecting from said rock shafts, first links connecting said first arms to said treadles, second links connecting said second arms to said weight means.
7. A device of the character described comprising a door having vertically movable elements movable upwardly to open position and downwardly to closed position, guide and stop means at the side of the door for guiding the vertical movement of said elements and limiting their downward travel, first treadles and second treadles, weight means holding the door in closed position, operating connections between the first and second treadles for elevating said weight means, counterweight means operatively connected to the door and to said operating connections, said counterweight means being operative by gravity upon elevation of said weight means to operate said movable elements of the door to elevated open position, pulley, shaft and cable means connecting said counterweight means with said elements of the door.
8. A device of the character described comprising a door having vertically movable elements movable upwardly to open position and downwardly to closed position, guide and stop means at the side of the door guiding the vertical movement of said elements and limiting their downward travel, first treadles and second treadles, weight means holding the door in closed position, operating connections between the first and second treadles for elevating said weight means, counterweight means operatively connected to the door and to said operating connections, said counterweight means being operative by gravity upon elevation of said weight means to operate said movable elements of the door to elevated open position, said operating connections comprising crossed and pivoted lever means.
9. A device of the character described comprising a door having vertically movable elements movable upwardly to open position and downwardly to closed position, guide and stop means at the side of the door guiding the vertical movement of said elements and limiting their downward travel, first treadles and second treadles, weight means holding the door in closed position, operating connections between the first and second treadles for elevating said weight means, counterweight means operatively connected to the door and to said operating connections, said counterweight means being operative by gravity upon elevation of said weight means to operate said movable elements of the door to elevated open position, pulley and cable means operatively connected between said door and said counterweight means.
10. A device of the character described comprising a door having vertically movable elements movable upwardly to open position and downwardly to closed position, guide and stop means at the side of the door guiding the vertical movement of said elements and limiting their downward travel, first treadles and second treadles, weight means holding the door in closed position, operating connections between the first and second treadles for elevating said weight means, counterweight means operatively connected to the door and to said operating connections, said counterweight means being operative by gravity upon elevation of said weight means to operate said movable elements of the door to elevated open position, upper and lower dashpot stop means for cushioning and limiting the upper and lower extremities of movement of said weight means.
